UNITED STATES PATENT OFFICE

2,541,903

AUTOMATICALLY SELECTIVE INDEXED
MEMORANDUM DEVICEFortunato S. Ajero, Chicago, Ill., assignor to
Mary Lee Hyre, Antioch, Ill.

Application March 29, 1946, Serial No. 658,317

5 Claims. (Cl. 40—104)

1

This application is a continuation-in-part of my abandoned application Serial No. 551,163, filed August 25, 1944, which in turn was a continuation-in-part of my abandoned application Serial No. 537,957, filed May 29, 1944.

The present invention relates to improved memorandum devices, and more particularly to an improved indexed memorandum device which automatically exposes a pre-selected memorandum page when the cover of said device opens.

My invention comprises a receptacle provided with a cover hinged thereto, spring means to urge said cover to the open position, a plurality of indexed memorandum sheets in said receptacle, and means to pre-select a number of said sheets to swing upwards with the opening cover thereby exposing the particularly desired memorandum sheet for immediate reference.

In a preferred form of my invention, the selection of the desired memorandum page and the release of the cover latch is accomplished by actuation of one knob in a single motion, thereby permitting the user of the device free and full employment of one hand while speedily exposing the desired reference with the other hand.

Previous known automatically selective memorandum devices have possessed certain disadvantages which are cured by my invention. Heretofore, in such articles, it has been necessary to set the selecting means and release the cover by operating unrelated knobs, slides, or buttons at separate points upon the device. The user could not operate the selecting mechanism and release the cover simultaneously without employing both hands. In the preferred form of my invention the desired reference may be selected and the cover opened by a single, uninterrupted motion of rotation and pressure upon one knob. The user will find this preferred embodiment of my invention particularly convenient if he is engaged in telephone conversation or otherwise has one hand occupied when he requires a reference. Since there is no wasted motion in moving the hand from selecting means to cover release latch, the operation of this preferred form of my invention is considerably faster than that of the previously known devices.

The selector arm of my invention is set by rotation of a knob at the end of a shaft upon which the selector arm is pivoted. Most of the prior art devices employ a slide and track index which is more expensive to manufacture and assemble and more prone to misalignment and breakage than my invention. Slots in the covers of prior art devices to form ways for the slide index permit the entry of dust and dirt to the

2

memoranda. My invention contains the memoranda in a complete enclosure where they cannot be soiled. My invention incorporates a pencil or pen-bearing socket which presents itself ready to the hand of the user as the cover opens thus enhancing the convenience of the device. My invention is simple and relatively inexpensive to manufacture, and the movement of parts therein is minimized thus affording the device a compactness which leads to streamlined and attractive design.

The principal object of my invention, therefore, is to provide an improved automatically selective, indexed memorandum device which is sturdy, inexpensive, efficient, and attractive.

Another object of my invention is to provide an improved automatically selective, indexed memorandum device in which the selection of the desired reference and release of the cover may be accomplished by a simple, uninterrupted motion of the hand at one place upon the device.

Yet another object of my invention is to provide a device of the character described that presents a writing means ready to the hand as the cover opens thus enhancing the convenience of said device to the user thereof.

Still another object of my invention is to provide such a device in which the memoranda therein are fully protected from dirt and damage.

The foregoing and such other advantages, objects, and capabilities as may appear herein or be pointed out as this description proceeds, or as are inherent in the present invention, are illustrated in the accompanying drawings, in which:

Figure 1 is a plan view of a preferred embodiment of my invention;

Figure 2 is a front view taken in section on the line 2—2 of Figure 1;

Figure 3 is a detailed front view of the selector and cover release mechanism also taken in section on the line 2—2 of Figure 1;

Figure 4 is a front elevational view of the device of Figure 1 in open position;

Figure 5 is a perspective view of the spring arm which constrains the cover to the base in closed position in the device of Figure 1;

Figure 6 is a fragmentary front view taken in section on the line 6—6 of Figure 1, and showing a hinged connection of the memorandum sheets and a means for fastening the memorandum pad to the base of the device; and

Figure 7 is a rear view in section on the line 7—7 of Figure 1; and illustrating the mounting and operation of the pencil socket by the opening cover.

Like reference characters are used to designate

similar parts in the drawings and in the description of invention which follows.

Referring now more particularly to the drawings, my improved automatically selective, indexed memorandum device 10 includes a base 11 and a cover 12. The cover 12 is formed with a peripheral flange 13 (Figures 2 and 4) which fits closely upon the base 11 at the two sides and one end of the device 10 when said cover 12 is closed. At the other end of the device 10 the cover 12 is hinged to the base 11 by two pins 14 and 15 journaled in base flanges 16 and 17 respectively and in the peripheral cover flange 13 (Figure 1). At this hinged end of the device 10 the cover flange 13 terminates slightly short of the base 11 as it must clear the base when the cover 12 rotates to open. A torsion spring 18 is positioned about the pin 14 with the ends of said spring constrained between the cover 12 and the base 11. Thus, the tension in said spring 18 is constantly urging the cover 12 to rotate up from the base 11 into the open position, and the force of said spring 18 is sufficient to lift the cover 12 when said cover is not latched to the base.

As best illustrated in Figures 4 and 7, a pencil socket 19 is journaled upon the hinge-pin 15. The socket 19 is formed with a lug 20 projecting in the path of the cover flange 13. When the cover 12 is opening the flange 13 pushes upon the lug 20 thus rotating the socket 19 to present a pencil 21 in said socket ready to the hand of the user. When the cover 12 is closing, gravity brings the socket 19 into its rest position upon the base 11. A stop 22 formed in the base 11 limits the rotation of the opening cover 12. The stop 22 is not extended to intercept the lug 20, therefore the socket 19 is restrained only by the cover flange 13 from falling back upon the base 11. Said socket 19 is thus free to follow a greater angle of rotation if the pencil 21 is plucked therefrom at such greater angle.

The base 11 is formed with a transverse depression 23 at the head or hinged end of the device 10. A base plate 24 (Figures 2 and 6) is riveted to the base 11 in this depression 23 at points 25, 26 and 27 (Figure 1). A pair of male fingers 28 and 29 project from the base plate 24 to engage female perforations in the back member 30 of the stack of memorandum cards 31. The memorandum cards 31 are hingedly connected to each other through perforations at one edge of each card by the plurality of rings 32, 33, 34 and 35 (Figures 1 and 6). The memorandum cards 31 are thus retained to the base 11 through the back member 30 yet said cards 31 are individually free to swing open with the cover 12 when selected to do so in a manner presently to be described.

The cards 31 terminate remote from their hinged ends in arcuate tabs 36 subtended by equal radii and by central angles which decrease in equal increments from card to card from the top to the bottom of the stack (Figures 1 and 2). The top card in the stack thus has the tab of the longest arc length and the bottom card of the stack has the tab of the shortest arc length.

Holes 37 and 38 in the cover 12 and base 11 respectively are aligned with perforations 39 in the cards 31 at the centers of the arcuate tabs 36 (Figure 3). A shaft 40 is centered in the perforations 39 and the cover hole 37 and said shaft 40 terminates in a knob 41 above the cover 12. The knob 41 is formed with a hexagonal recess 42 into which is slidably fitted a hexagonal adapter 43. A helical spring 44 around the shaft 40 is constrained in the hexagonal recess 42 between the

knob 41 and the adapter 43. An index pointer 45 is integrally formed upon the adapter 43 and rotates with said adapter to sweep the arc of the index notations upon the cover 12 indicated by the letters of the alphabet in Figure 1.

The adapter 43 is formed with a square recess 46 and a cylindrical bore 47 (Figure 3). A squarely-shaped sleeve 48 is press-fitted into the recess 46 to project through the cover hole 37. Below the cover 12, the squarely-shaped sleeve 48 carries a ratchet arm 49 immediately below and aligned with the index pointer 45. The tip of the ratchet arm 49 is formed with a dimple 50 to cup the ratchet projections 51 in the under surface of the cover 12 along the arc of the alphabet index. The squarely-shaped sleeve 48 also carries a selector arm 52 which terminates in a hook 53 the free end of which extends beneath the arcuate tabs 36.

It is now apparent that if the selector arm 52 swings upward with the cover 12 as the latter opens, the hook 53 will engage some of the arcuate tabs 36 and swing the cards 31 of those engaged tabs 36 up with said cover. The number 20 of the arcuate tabs 36 engaged by the hook 53 depends upon the position of the selector arm 52. Referring to Figure 1, if the selector arm 52 is positioned at the top of the arc of its travel, the hook 53 will engage only those tabs 36 of longest arc length and the great majority of the cards 31 will remain resting upon the base 11 as the cover 12 opens. If the selector arm 52 is positioned at the bottom of the arc of its travel, the hook 53 will engage even the tabs 36 of very short arc length and will swing most of the cards 31 with the opening cover. It is apparent that the cards 31 may be individually designated by the letters of the alphabet index on the cover 12, and that the rotation of the index pointer 45 may be calibrated with the rotation of the selector arm 52, whereby the indication of a letter by the pointer 45 will position the selector arm 52 to swing with the opening cover all the cards 31 above the card designated by the indicated letter thereby exposing the selected card at the top of the stack which remainss resting upon the base 11.

Referring now to Figure 3 as the best illustration, a cylindrical sleeve 54 is press-fitted into the bore 47 of the adapter 43 and into the bore 55 of the squarely-shaped sleeve 48. The cylindrical sleeve 54 projects through the base hole 38 and terminates in a first annular flange 56 immediately below the base 11. A second annular flange 57 is formed upon the cylindrical sleeve 54 immediately below the squarely-shaped sleeve 48.

The shaft 40 is paired with the bore 58 of the cylindrical sleeve 54. A collar 59 is slidably fitted upon said sleeve 54 between the first annular flange 56 and the second annular flange 57. This collar 59 is keyed by the pin 60 to the shaft 40 through the slots 61 and 62 in the sleeve 54. A spring arm 63, whose shape is disclosed by Figure 65, is riveted to the base 11 through the hole 64 in its head 65. The flat tip 66 of said spring arm 63 is twisted and engages the first annular flange 56 of the cylindrical sleeve 54 at the angle shown in Figure 3. The sleeve 54 is thus restrained from upward movement. Since the sleeve 54 is tightly pressed within the bore 47 of the adapter 43 which adapter in turn bears upon the cover 12, said cover is thus restrained in the closed position upon the base 11.

The cover 12 is released to rotate to the open

position by slight pressure upon the knob 41. Such pressure depresses the shaft 40 causing the collar 59 to slide down upon the sleeve 54. The collar 59 wedges the flat tip 66 of the spring arm 63 from engagement with the flange 56. The deflection of the tip 66 is permitted by the cutout 67 in the base 11 (Figure 1). The sleeve 54 is freed for upward movement and the cover 12 is no longer constrained to the base 11. The cover spring 18 has sufficient force when the pressure of the hand is released at the knob 41 to rotate the cover 12 to the limit of the stop 22. The hand of the user, in drawing away from the knob 41, restrains the cover 12 from snapping back too sharply and the entire movement of said cover in opening is fast and smooth.

Selection of the desired reference is made by rotation of the knob 41. Said rotation of the knob 41 rotates the adapter 43 and the index pointer 45. Rotation of the adapter 43 in turn causes the rotation of the squarely-shaped sleeve 48 and the positioning of the selector arm 52. It is thus apparent that the user may select the desired reference by rotation of the knob 41 and, without further fumbling at another point on the device, a slight pressure upon the same knob 41 will release the cover 12 exposing the selected card for the reference of the user. The open position of the device 10 is shown in Figure 4. In order to close the device, the cover 12 is merely pressed back upon the base 11. The spring 44, when hand-pressure was released at knob 41, has caused the shaft 40 and the collar 59 to move up the sleeve 54. The tip 66 of the spring arm 63 thus can reengage the flange 56 and re-lock the cover 12 to the base 11.

I prefer to construct my invention of synthetic plastic materials as I have found such materials lend themselves to practical, inexpensive and attractive structures. I have also found that the use of such materials permits the press-fitting of contiguous surfaces (such as for example the sleeve 54 in the bore 47) to join such surfaces so tightly as to eliminate the necessity of screw threads or similar expedients. However, while I have described my invention as embodied in a specific form and operating in a specific manner for the purposes of illustration, it should be understood that I do not limit my invention thereto, since various modifications will suggest themselves to those skilled in the art without departing from the spirit of my invention, the scope of which is set forth in the annexed claims.

I claim:

1. An automatically selective, indexed card device comprising: a base; a cover hingedly mounted upon said base; spring means to urge said cover in rotation from said base; a plurality of indexed cards fastened upon said base, said cards being hingedly fastened to each other and terminating in arcuate tabs subtended by equal radii and by central angles decreasing in equal increments from the top card to the bottom card, said cards each having a perforation at the center of said arcuate tabs, said cover having an opening aligned with said perforations; a shaft centered in said perforations and said opening in said cover a knob at one end of said shaft above said cover; a spring in said knob about said shaft; an adapter slidably journaled in said knob against said spring; an indicating arm carried by said adapter; a first sleeve press-fitted into said adapter and journaled in said cover; a selector arm carried by said first sleeve, said selector arm terminating in a hook extending about said tabs;

a second sleeve paired with said shaft and press-fitted into said adapter and said first sleeve; a flange upon the end of said second sleeve below said base; a spring arm fastened to said base and engaging said second sleeve at said flange; and a collar slidably upon said second sleeve and keyed to said shaft, whereby depression of said shaft causes said collar to wedge said spring arm from engagement with said second sleeve and frees said cover to rotate up from said base.

5 2. An automatically selective, indexed memorandum device comprising: a base; a cover hinged to said base; spring means urging said cover up from said base; a plurality of flat members resting upon said base, said flat members having aligned perforations therein, said cover having an opening therein aligned with said perforations; said flat members being hingedly fastened together and terminating in arcuate tabs subtended by equal radii and by central angles decreasing in equal increments from the top flat member to the bottom flat member; a shaft centered in said perforations of said flat members and said opening in said cover; a knob at the end 10 of said shaft above said cover; an indicating arm rotatable by said knob, said selector arm terminating in a hook the free end of which extends beneath said arcuate tabs; a flanged sleeve upon said shaft; a spring arm fastened to said base and engaging the flange of said sleeve; and a collar keyed to said shaft and slidably upon said sleeve, whereby depression of said shaft causes said collar to wedge said spring arm from engagement with 15 said flanged sleeve and frees said cover to rotate up from said base.

20 3. An indexed memorandum device comprising: a receptacle and a hinged cover therefor; a spring means urging said cover to open; a plurality of hinged memorandum sheets terminating in graduated arcuate tabs, said cover and said memorandum sheets each having an opening therein aligned with the center of said arcuate tabs; a shaft centered in said openings in said memorandum sheets and said cover; a knob at 25 the end of said shaft above said cover; a selector arm rotatable by said knob, said selector arm terminating in a hook the free end of which extends beneath said tabs; a flanged sleeve about said shaft; a spring arm fastened to said receptacle and engaging the flange of said sleeve; and a collar keyed to said shaft and slidably upon said sleeve, whereby depression of said shaft causes said collar to pry said spring arm from engagement with said flanged sleeve and frees said cover to rotate up from said receptacle.

4. An automatic memorandum device comprising: a receptacle and a cover therefor; a plurality of hinged memorandum sheets terminating in graduated arcuate tabs, said sheets and said cover each having an opening therein aligned substantially with the center of said arcuate tabs; a shaft in said openings in said cover and said memorandum sheets; a selector arm rotatable by 40 said shaft, said selector arm terminating in a hook the free end of which extends about said tabs; a flanged sleeve about said shaft; a spring arm extending from said receptacle to engage the flange of said sleeve; and means keyed to said shaft whereby the depression of said shaft pries said spring arm from engagement with said flanged sleeve and releases said cover.

5. An automatically selective, indexed card device consisting of: a base; a hinge-pin journaled in said base; a flanged cover pivotally mounted

thereupon; helical spring means about said hinge-pin to urge said cover in rotation from said base; a stack of indexed cards hingedly fastened to each other and terminating in arcuate tabs subtended by equal radii and by central angles decreasing in equal increments from card to card from top to bottom of said stack, said cards each having a perforation at the center of said arcuate tabs, said base and said cover each having an opening aligned with the said perforations; a back plate at the bottom of said stack hinged with said cards and fastened to said base; a cylindrical shaft centered in said perforations and said openings in said cover and said base; a hexagonally-recessed knob at the end of said shaft above said cover; a spring in said knob around said shaft; a hexagonally-shaped, squarely-recessed adapter slidably journaled in said knob against said spring; a pointer carried by said adapter; an index ratchet in said cover; a squarely-shaped sleeve press-fitted into said adapter; a ratchet arm carried by said squarely-shaped sleeve and engaging said index ratchet to removably secure said knob in any desired position; a selector arm also carried by said squarely-shaped sleeve, said selector arm terminating in a hook extending about said arcuate tabs of said cards; a cylindrical sleeve paired with said shaft and press-fitted into said adapter and into said squarely-shaped sleeve; a first annular flange upon the end of said cylindrical sleeve below said base; a second annular flange upon said cylin-

drical sleeve above said first annular flange; a spring arm fastened to said base and bearing upon said cylindrical sleeve at said first annular flange; a collar slidably fitted upon said cylindrical sleeve between said first and said second annular flanges; a slot in said cylindrical sleeve; and a pin extending through said slot to drivably connect said shaft to said collar, whereby depression of said shaft causes said collar to wedge said spring arm from engagement with said cylindrical sleeve and frees said cover to rotate up from said base.
